V. BEAUREGARD

HAIR CLIPPER

Filed Jan. 15, 1927

Inventor:
Victor Beauregard,
by High & Brown, Zimber, May,

Atty.

UNITED STATES PATENT OFFICE.

VICTOR BEAUREGARD, OF BOSTON, MASSACHUSETTS.

HAIR CLIPPER.

Application filed January 15, 1927. Serial No. 161,309.

This invention relates to a hair-clipper including toothed blades contacting with each other, one being fixed and the other adapted to reciprocate, the toothed portions 5 of said blades being comb-shaped, and the teeth of the two blades being formed to cooperate in severing hairs in the spaces between adjacent teeth, when the movable blade is reciprocated.

10 The chief object is to provide a hair-clipper adapted to operate both in recessed surfaces, such as the ear cavities, and on external surfaces, such as the back of the head and the adjoining portion of the neck.

15 Of the accompanying drawings forming a part of this specification,—

Figure 1 is a side view of a clipper embodying the invention, a portion being broken away.

20 Figure 2 is a section on line 2—2 of Figure 1.

Figure 3 is an edge view.

Figure 4 is an enlarged section on line 4—4 of Figure 1.

25 Figure 5 is an enlarged section on line 5—5 of Figure 1.

Figure 6 shows in perspective the holder and the clamping screw hereinafter described, the separable side plate of the holder being removed.

Figure 7 shows in perspective the slide which reciprocates the movable blade.

Figure 8 shows in perspective the separable side plate.

35 Figure 9 shows in perspective the fixed blade.

Figure 10 shows in perspective the movable blade.

Figure 11 shows in perspective the bell-crank lever shown by Figure 1.

40 Figure 12 is a view similar to Figure 4, showing the blades curved instead of flat.

The same reference characters indicate the same parts in all of the figures.

45 The body portion 12 of the holder element of my improved clipper is provided at one end with a handle 13. Projecting side by side from the opposite end of the holder are two narrow oblong toothed blades 14

50 and 15, having unobstructed outer ends, formed to enter a cavity such as that of the human ear. The inner end of the blade 14 is fixed, as by a clamping screw 16 to the holder. The blade 15 is movably connected with the holder, preferably as

hereinafter described, means being provided for reciprocating said blade longitudinally. The teeth 17 of the blades are separated by hair-receiving spaces, and are adapted as usual in clippers of this type, to sever hairs 60 in said spaces, when the movable blade is reciprocated. The movable blade is preferably reciprocated by the means next described.

The holder includes the body portion 12, 65 shown by Figure 6, and the separable plate 12^a shown by Figure 8, and is provided with an internal guideway, formed in part by a recess 18 (Figures 5 and 6) in one side of the body portion, and in part by the 70 plate 12^a.

A slide composed of a body portion 19, and a tongue portion 19^a, is movable in and guided by the guideway. The tongue portion projects from the holder beside the 75 fixed blade 14, and is offset from the latter, as shown by Figures 2 and 7, so that a space is provided between the fixed blade and the tongue portion which receives the inner end of the movable blade. The movable blade 80 is fixed to the tongue 19^a by a bolt 20, preferably having a clamping nut 20^a as shown by Figure 4. The inner end of the fixed blade bears on a recessed seat 18^a (Figure 6) at one end of the recess 18, and is clamped 85 against said seat by the screw 16, the edge of the blade at the inner end thereof, bearing on surface portions of the recess, so that the blade is rigidly confined.

The holder is provided with an ear 21, 90 to which is fulcrumed by a pin 22, a bell-crank lever including a shorter arm 23, extending through a slot 24 (Figure 6) in the holder, and entering a slot 25 (Figure 7) in the slide 19, and a longer arm 26, 95 movable by a digit of a hand grasping the handle 13, as indicated by broken lines in Figure 1, to move the slide and the movable blade in one direction. A spring 27 (Figure 1) fixed at one end to the holder 100 and bearing at its opposite end on the lever arm 26, acts on the lever to move the slide and the movable blade in the opposite direction.

It will now be seen that the clipper may 105 be conveniently operated to cut hairs in an ear cavity by inserting the narrow unobstructed outer ends of the blades in the cavity and reciprocating the movable blade. The length of the blades is such that the 110

clipper may be conveniently operated to trim hair on external surfaces of the head and neck.

The blades 14 and 15 may be curved, so that the cross section of each blade has a convex and a concave curvature, one side of the tongue 19^a being correspondingly curved, as shown by Figure 12. This form enables the distance between the outer side of the fixed blade 14, and the outer end of the bolt 20, to be decreased. The movable blade 15 is provided with a hole 30, spaced from the hole 31 which receives the bolt 20, and receiving a pin 32, fixed to the tongue 19^a to prevent possibility of the turning of the movable blade on the bolt.

The movements of the slide 19 may be limited by a stop pin 33, entering a recess 34 in the slide.

20 I claim:

1. A hair-clipper adapted to operate in recessed and on external surfaces, the clipper comprising a holder having a handle at one end and an internal guideway, two narrow oblong toothed blades projecting side by side from the opposite end of the holder and having unobstructed outer ends formed to enter a cavity, one blade being fixed to the holder, and the other movably connected therewith, a slide movable in the guideway and fixed to the movable blade, and means for longitudinally reciprocating the slide and the movable blade, the teeth of said blades being separated by hair-receiving spaces and adapted to sever hairs in said spaces when the movable blade is reciprocated.

2. A hair-clipper adapted to operate in recessed and on external surfaces, the clipper comprising a holder having a handle at one end and an internal guideway, two narrow oblong toothed blades projecting side by side from the opposite end of the holder, and having unobstructed outer ends formed to enter a cavity, one blade being fixed to the holder, and the other movably connected therewith, a slide movable in the guideway and fixed to the movable blade, a bell-crank lever fulcrumed on the holder and including a shorter arm engaged with the slide, and a longer arm movable by a digit of a hand grasping the handle to move the slide and

the movable blade in one direction, and a spring acting on the lever to move the slide and the movable blade in the opposite direction. 55

3. A hair-clipper comprising a holder having a guideway and a handle projecting from one of its ends, one side of the guideway being recessed to form a seat, a narrow oblong toothed fixed blade clamped at one end against the seat and projecting from the opposite end of the holder, a slide including a body portion, movable in the guideway, and a tongue portion projecting from the body portion and from the holder beside the fixed blade, and offset from the latter, to provide a movable blade-receiving space, and a narrow oblong movable blade fixed to the tongue portion in said space and contacting with the fixed blade, and means for reciprocating the movable blade, the outer ends of the blade being unobstructed and formed to enter a cavity, the teeth of said blades being separated by hair-receiving spaces, and adapted to sever hairs in said spaces when the movable blade is reciprocated. 70

4. A hair-clipper comprising a holder having a guideway and a handle projecting from one of its ends, one side of the guideway being recessed to form a seat, a narrow oblong toothed fixed blade clamped at one end against the seat and projecting from the opposite end of the holder, a slide including a body portion, movable in the guideway, and a tongue portion projecting from the body portion and from the holder beside the fixed blade, and offset from the latter, to provide a movable blade-receiving space, and a narrow oblong movable blade fixed to the tongue portion in said space and contacting with the fixed blade, a bell-crank lever fulcrumed on the holder and including a shorter arm projecting into the guideway and engaged therein with the slide, and a longer arm movable by a digit of a hand grasping the handle to move the slide and the movable blade in one direction, and a spring acting on the lever to move the slide and the movable blade in the opposite direction. 90

In testimony whereof I have affixed my signature.

VICTOR BEAUREGARD.
